CARBURETOR FOR HIGH-PRESSURE VALVES

John Berrien Rogers, Pasadena, Md.

Application May 10, 1948, Serial No. 26,173

12 Claims. (Cl. 302—46)

1

This invention is a novel carburetor for high pressure valves used in connection with apparatus for feeding granular or finely divided solid material from a feed hopper at atmospheric pressure into a mixing chamber having a pressure above atmospheric, in a continuous operation, the present invention being an improvement upon that disclosed in my U. S. Letters Patent No. 2,428,995, issued October 14, 1947; also upon my joint application Serial No. 772,034, filed September 4, 1947, now abandoned. While the invention is susceptible to many applications, the same is particularly adapted for feeding pulverized coal for thorough mixture with a stream of high pressure air passing through said carburetor.

The principal object of the present invention is to provide novel means of mixing air and a finely divided or pulverized coal in as nearly perfectly constant proportions as possible. The pulverized coal is introduced into my carburetor by means of the feed throat valve arranged to bring the coal into the carburetor in an almost perfectly even flow, it being the function of the carburetor to mix this even flow of coal into an even flow of air in as nearly perfectly constant proportions as possible. To do this, the coal must be first removed from its point of entry, i. e., the perimeter of the valve seat, immediately and completely; and secondly, the coal must be thoroughly mixed into the air immediately after its removal from the valve seat.

A further object of the invention is to provide a carburetor of the above type in which the air is initially brought tangentially into a distribution chamber disposed at the inner portion of the carburetor to impart to the air a rotary motion around the feed throat which distributes the air evenly with respect to an annular series of louvres separating the distribution chamber and a mixing chamber disposed at the outer portion of the carburetor. These louvres are pitched at an acute angle to the flow of the air and their combined area is such that with the proper volume and pressure the rotation of the air is increased greatly and its velocity is stepped up to a point where it will remove the solid material from the feed throat valve in a positive manner. These louvres are disposed in such a manner that the whirling high velocity air in the mixing chamber is directed onto and completely around the perimeter of the feed throat valve seat which accomplishes the first of my objectives. The second objective is attained by simply allowing the solid material and high velocity air to whirl around within the mixing chamber. From the distribution side of

2

the louvres on—and as far as desired to convey it pneumatically, the velocity of the air is never allowed to fall below 5000 feet per minute—this velocity in the mixing chamber creating an intense turbulence which thoroughly mixes the solid material with the air.

Thus it can be seen that I accomplish the first of my objectives by supplying air at a great enough velocity to insure the removal (of the solid material) as fast as it is fed through the feed valve and with enough pressure to make the operation perfectly positive. The second objective is accomplished by the great turbulence created by the high velocities used.

15 I will explain the invention with reference to the accompanying drawing, which illustrates one practical embodiment thereof to enable others familiar with the art to adopt and use the same; and will summarize in the claims the novel 20 features of construction, and novel combinations of parts, for which protection is desired.

In said drawing:

Figure 1 is a longitudinal section through the carburetor, showing the feed throat, valve, and 25 adjacent parts of the hopper.

Fig. 2 is an end elevation taken on the line 2—2, Fig. 1, showing the louvres formed between the distribution chamber and mixing chamber to impart whirling motion to the primary air as it 30 enters the mixing chamber.

Fig. 3 is a section, partly in elevation, on the line 3—3, Fig. 2.

The feed hopper 1 is provided with a bottom 35 1a and an opening 1b in its end communicating with the inlet of a cylindrical feed throat casing 2 having an inner wall 2a adapted to be secured, by bolts 3 or the like, to the end of hopper 1.

Extending axially through the feed throat 2 is a shaft 4 having a reduced end journaled in the 40 far end wall of an annular mixing chamber 5, hereinafter described, said end wall having a bore 5a receiving the reduced end of the shaft 4 and having an antifriction bearing 6 housed in an enlarged bore 5b of the end wall. The outer end 45 of bore 5b is covered by a cap or plate 7 (Fig. 1), and a suitable packing 8 is interposed between shaft 4 and an intermediate bore 5c in the end wall which packing 8 is compressed by a ring 9 threaded into the tapped outer end of the intermediate bore 5c, as shown.

Around the feed throat 2 is an annular chamber A for primary air distribution, the chamber A being formed between the exterior of the feed throat 2 and the inner wall 2a of the feed throat 55 casing and an annular outer wall 2b and an outer

end wall 2c, the primary air, under pressure, being introduced thereto through a pipe 10 which enters the lower portion of chamber A at an angle to or substantially tangent to chamber A, thus causing the air within said chamber to have a rapid swirling motion around the feed throat 2.

In the end wall 2c of chamber A are a series of louvres 2d preferably, but not necessarily, formed integrally therewith, the louvres 2d discharging into an annular mixing chamber B formed between the end wall 2c of the feed throat casing and the annular mixing chamber casing 5, as shown, whereby the air discharged through the louvres at an acute angle to the rotary motion of air in chamber A, will likewise have a swirling motion, the air emerging from a tangentially arranged outlet 5d in the top of the mixing chamber B. As shown, the mixing chamber casing 5 has an inwardly extending hub portion 5e for the bearing for shaft 4, said hub portion imparting an annular shape to the mixing chamber B, and the hub portion terminating adjacent the outer face of the end wall 2c of the air distribution chamber A.

The outer end of the bore of the feed throat 2 is internally beveled as at 2e (Fig. 1) and a disc-like valve 12, of rubber or other yieldable material, is keyed on shaft 4 and has a beveled outer edge 12f corresponding with the beveled portion 2e of the feed throat, as shown in Fig. 1, a round-edged collar 13 around shaft 4 being interposed between the inner end of the hub 5e of casing 5 and the outer face of valve 12. The shaft 4 carries a conveyor flight 4b whose periphery makes a close contact with the bore of feed throat 2, the flight terminating adjacent the inner face of valve 12, but extending into the hopper.

The flight 4b during rotation of shaft 4 draws the finely divided coal or other material from hopper 1 and passes it outwardly of the feed throat 2, past the valve 12 and into the mixing chamber B. The resiliency of the material of valve 12, whether it be rubber, plastic or metal, will cause the beveled periphery 12f of the valve to normally seat against the beveled portion 2e of the feed throat, but as the pulverized material is forced out of the feed throat the resiliency of valve 12 will cause same to accommodate itself to any fluctuations in the flow of the finely divided or granular solid material. Thus in any case whether the feed hopper is empty or material is flowing, the valve 12 forms a seal which will prevent the high pressure in the mixing chamber B from escaping backwardly through the feed throat 2 into hopper 1, from whence the same could pass directly into the atmosphere.

A secondary function of valve 12 is to cause the finely divided coal or other material to flow more evenly to the mixing chamber B, said valve being fixedly mounted on the shaft 4 and rotating with the material being fed by the flight 4a, thus reducing wear on the valve 12. In event the flow of material stops, the valve 12 will assume its normal sealing or closed position against the valve seat 2e and prevent loss of pressure from the mixing chamber B back through the feed throat.

The above construction provides novel means of mixing air and a finely divided solid material such as pulverized coal in as nearly perfectly constant proportions as possible. The solid material is introduced into the carburetor mixing chamber B by means of the feed throat valve 12 which valve will bring the solids into the carburetor mixing chamber B in an almost per-

fectly even flow, it being the prime function of the carburetor to mix this even flow of solid material into an even flow of air in as nearly perfectly constant proportions as possible. To do this the solid material must first be removed from its point of entry, i. e., the periphery 2e of the valve seat, immediately and completely; and secondly the coal must be thoroughly mixed into the air at once.

10 Air is brought tangentially into distribution chamber A by inlet 10 in such manner that the air has imparted thereto a rotary or swirling motion around the feed throat 2 thereby distributing the air evenly to the series of louvres 15 2d disposed between the distribution chamber A and the mixing chamber B. These louvres are pitched at an acute angle to the flow of the air and their combined area is such that, with the proper volume and pressure, the rotation of the 20 air is increased greatly and the velocity is stepped up to a point where it will remove the solid material from the feed throat valve in a positive manner. The louvres 2d are disposed in such a manner that the whirling high velocity air is directed on and completely around the perimeter of the feed throat valve seat 2e, which 25 accomplishes the first of my objectives. The second objective is attained by simply allowing the solid material and high velocity air to whirl 30 around in the mixing chamber B. From the distribution side of the louvres, as far as desired to convey the mixture pneumatically, the velocity of the air is never allowed to fall below 5000 feet per minute, the velocity in the mixing chamber 35 B creating an intense turbulence which thoroughly mixes the solid material with the air.

Thus it can be seen that I accomplish the first of my objectives by supplying air at a great enough velocity to insure that the removal of the solid material is as fast as it is fed and with enough pressure to make the operation perfectly positive. The second objective is accomplished by the great turbulence created by the high velocities which I used. The flexible feed throat 45 valve 12 eliminates any back pressure and causes the pulverized coal to enter the mixing chamber B in a perfectly even flow. The primary air is brought into the mixing chamber B through the louvres 2d which are disposed at a very acute 50 angle to the flow of the air imparting a rotary motion to the air entering the mixing chamber. The areas of the louvres 2d and throughout the mixing chamber B are such that in combination with the pressure of the primary air a velocity 55 of more than 5000 feet per minute is maintained at all times. The primary air is brought into the carburetor at 10, tangentially, which causes it to flow around the feed throat 2 and through the distribution chamber A in a swirling manner 60 which distributes it evenly to the louvres 2d, the air rotating in the desired direction. The primary air and coal mixture leave the carburetor through pipe 5d which is disposed tangentially on the far side of the mixing chamber B.

65 I claim:

1. In combination with a hopper for finely divided solid material, a carburetor for mixing said material at atmospheric pressure with air above atmospheric pressure, comprising a feed throat 70 extending from the hopper; a shaft extending through said throat; a conveyor flight on the shaft terminating adjacent the discharge end of said throat, the periphery thereof slidably engaging the walls of said bore; a wall enveloping the feed throat and forming therewith an annu-

lar air distribution chamber closed at both ends; an annular casing contiguous to the outer end of the distribution chamber beyond the throat and forming an annular mixing chamber; a resilient valve within the mixing chamber and normally closing the outer end of the throat; the outer end of the distribution chamber having an annular series of louvres therein inclined in the same direction and discharging into the mixing chamber; a tangentially disposed inlet for air under pressure into the distribution chamber; and a tangentially disposed outlet from the mixing chamber.

2. In combination as set forth in claim 1, said louvres being disposed at an acute angle to the swirling movement of the air in the distribution chamber, and being of such combined area that the air volume and pressure of the swirling air chamber will immediately remove the material as it is discharged past the said valve, the air and material swirling within the mixing chamber before passing through the said outlet.

3. In a combination as set forth in claim 1, the combined area of louvres being such that the minimum air velocity within the mixing chamber will be substantially 5000 feet per minute, thereby setting up an intense turbulence therein to thoroughly mix the solid material with the air.

4. In combination with a hopper for finely divided solid material, a carburetor for mixing said material at atmospheric pressure with air above atmospheric pressure, comprising a cylindrical feed throat having a bore communicating with the hopper; a shaft extending through said bore; a conveyor flight on the shaft terminating adjacent the discharge end of said bore, the periphery of said flight slidably engaging the walls of said bore; the outer end of said bore being internally beveled to form a valve seat; an annular wall around and spaced from the feed throat and forming an annular air distribution chamber closed at both ends; an annular casing contiguous to the outer end of the distribution chamber beyond the throat and forming an annular mixing chamber; a resilient valve mounted on and rotating with the shaft within the mixing chamber and having a beveled periphery normally seating upon and closing the valve seat; the outer end of the distribution chamber having an annular series of louvres therein inclined in the same direction and discharging into the mixing chamber; a tangentially disposed inlet into the distribution chamber for air under pressure; and a tangentially disposed outlet from the mixing chamber.

5. In a combination as set forth in claim 4, said louvres being disposed at an acute angle to the swirling movement of the air in the distribution chamber, and being of such combined area that the air volume and pressure of the swirling air will immediately remove the material as it is discharged past the said valve, the air and material swirling within the mixing chamber before passing through the said outlet.

6. In a combination as set forth in claim 4, the combined area of louvres being such that the minimum air velocity within the mixing chamber will be substantially 5000 feet per minute, thereby setting up an intense turbulence therein to thoroughly mix the solid material with the air.

7. In combination with a hopper for finely divided solid material, a carburetor for mixing said material at atmospheric pressure with air above atmospheric pressure, comprising a cylindrical feed throat having a bore communicating with

the hopper; shaft extending through said bore; a conveyor flight on the shaft terminating adjacent the discharge end of said bore, the periphery of said flight slidably engaging the walls of said bore; the outer end of said bore being internally beveled to form a valve seat; an annular wall around and spaced from the feed throat and forming an annular air distribution chamber closed at both ends; a casing having an internal hub portion forming an annular mixing chamber contiguous to the outer end of the distribution chamber and beyond the said valve seat; a bearing for the shaft in the said hub; a resilient valve on said shaft within the mixing chamber and having a beveled periphery normally seating upon and closing the valve seat; the outer end of the distribution chamber having an annular series of louvres therein inclined in the same direction and discharging into the mixing chamber; a tangentially disposed inlet into the distribution chamber for air under pressure; and a tangentially disposed outlet from the mixing chamber.

8. In a combination as set forth in claim 7, said louvres being disposed at an acute angle to the swirling movement of the air in the distribution chamber, and being of such combined area that the air volume and pressure of the swirling air will immediately remove the material as it is discharged past the said valve, the air and material swirling within the mixing chamber before passing through the said outlet.

9. In a combination as set forth in claim 7, the combined area of louvres being such that the minimum air velocity within the mixing chamber will be substantially 5000 feet per minute, thereby setting up an intense turbulence therein to thoroughly mix the solid material with the air.

10. In combination with a hopper for finely divided solid material, a carburetor for mixing said material at atmospheric pressure with air above atmospheric pressure, comprising a cylindrical feed throat having a bore communicating with the hopper; a shaft extending through said throat; a conveyor flight on said shaft terminating adjacent the discharge end of said throat, the periphery of said flight engaging the walls of said bore; the outer end of said throat being internally beveled to form a valve seat; an annular wall around and spaced from the feed throat forming an annular air distribution chamber closed at both ends; a casing having an internal hub portion forming an annular mixing chamber contiguous to the outer end of the distribution chamber and beyond the said valve seat; a bearing for the shaft in the said hub of the mixing chamber casing; a resilient valve mounted on and rotating with the shaft within the mixing chamber and having a beveled periphery normally seating upon and closing the valve seat; a round edged collar on the shaft interposed between the inner end of the hub and the outer face of the said valve; the outer end of the distribution chamber having an annular series of louvres therein inclined in the same direction and discharging into the mixing chamber; tangentially disposed inlet into the distribution chamber for air under pressure; and a tangentially disposed outlet from the mixing chamber.

11. In a combination as set forth in claim 10, said louvres being disposed at an acute angle to the swirling movement of the air in the distribution chamber, and being of such combined

area that the air volume and pressure of the swirling air will immediately remove the material as it is discharged past the said valve, the air and material swirling within the mixing chamber before passing through the said outlet.

12. In a combination as set forth in claim 10, the combined area of louvres being such that the minimum air velocity within the mixing chamber will be substantially 5000 feet per minute, thereby setting up an intense turbulence therein to thoroughly mix the solid material with the air.
